UNITED STATES PATENT OFFICE

HARRY A. HEINEMAN, OF ST. LOUIS, MISSOURI.

SKIRT-SUPPORTER.

SPECIFICATION forming part of Letters Patent No. 660,545, dated October 23, 1900.

Application filed April 5, 1899. Serial No. 711,796. (No model.)

To all whom it may concern:

Be it known that I, HARRY A. HEINEMAN, a citizen of the United States, residing at St. Louis, in the State of Missouri, have invented 5 a new and useful Skirt-Supporter, of which the following is a specification.

My invention relates to improvements in devices for supporting the skirts of ladies' dresses and holding down the waists worn 10 with such skirts.

The chief objects of my improvements are, first, to provide improved means for suspending skirts from corsets; and, second, to provide a skirt-supporter which will not only 15 firmly support the skirt of a dress, but will hold down a separate waist worn with such skirt, and thus make the use of safety-pins and other similar means now used for keeping such waists in position unnecessary. I attain 20 these objects by mechanism illustrated in the accompanying drawings, in which—

Figure 1 is a view of a portion of a skirt suspended from a pair of corsets and a portion of a waist held in position by one of my 25 improved skirt-supporters, the corsets and the greater part of the skirt-supporter being indicated by dotted lines. Fig. 2 is a vertical section on line 2 2, Fig. 1. Fig. 3 is a 30 sectional view of the same parts shown in Fig. 2, but representing the underwaist, shirt-waist, and skirt as detached from the portion of the supporter attached directly to the corsets. Fig. 4 is a detailed view in elevation of a portion of a pair of corsets having a part 35 of my skirt-supporter attached thereto. Fig. 5 is an enlarged view of a detail. Fig. 6 is a 40 detailed view of the parts entering into the loop of my supporter ready to be put together, and Fig. 7 is a similar view of the loop when completed.

Similar letters refer to similar parts throughout the several views.

A represents a portion of the back of a pair of corsets whose parts *a* are secured together 45 in the usual manner by a lacing *a'*, passed through the eyelets *a''*.

B represents an underwaist, C a shirt-waist, and D the skirt of a dress.

In the preferred form of my device represented in the drawings, E represents a button having a shank *e* attached at its inner end to 50 a button-plate E', whose chief function is to

act as a guard and prevent the button from inconveniencing a wearer. The plate E', as shown, contains two perforations *e'*, one near each lower corner. These, though desirable, are not essential. A pair of upwardly-extending arms E² are shown attached to the plate by means of pivots *e²*, upon which they turn laterally. Each of said arms is provided 60 at its outer end with a hook E³, adapted to enter an eyelet *a²*, and preferably, though not necessarily, so formed as to prevent its accidental disengagement from an eyelet of a pair of corsets while they are laced and on 65 a wearer. In order to prevent such disengagement, I preferably make the top *e³* of the hook sufficiently long to strike the top of the eyelet engaged thereby when pushed upward unless the corset is bent and make the return-bend or tip *e⁴* of the hook longer than 70 the diameter of the eyelet it is intended to pass through, and preferably, though not necessarily, bend said tip *e⁴* back toward the arm E², with which it is connected, as shown most 75 clearly in Fig. 5. I also consider it advantageous to give the hook E³ a backward and outward curve *e⁵* at the back thereof, so as to make room therein for an eyelet and at the same time allow the arm E² to lie close 80 to the corset, and the parts are as shown in Figs. 2, 3, and 5. This arrangement enables the bottom plate E' of my device to be suspended from opposite eyelets of a pair of corsets regardless of whether the parts *a* are 85 near each other or are so laced as to remain a considerable distance apart, and my device can be attached in place in a moment and when hooked cannot be disengaged accidentally. Moreover, the arms E² cannot yield 90 longitudinally and are extremely durable.

The lateral adjustability of the arms E² may be secured by several well-known mechanical means besides those shown, which will at once suggest themselves to any good 95 mechanic as available substitutes for the means I have described, and I desire to cover all such known substitutes, as well as said special preferred means, where I refer to means for securing lateral adjustability in 100 general terms.

E⁴ represents a string or lacing passing through perforations in the plate E' and through eyelet-holes in the corsets and de-

signed to prevent the plate E' from swinging laterally. Though useful it is not essential.

- F represents a loop designed to be fastened to the band d of the skirt to be supported by means of threads f or other suitable means, which in the preferred construction are passed through the openings f' and around the base f². The loop contains an opening F', having an enlarged portion f³, to admit the inward passage of the head of the button E, and a contracted portion f⁴, designed to fit around the shank e of said button back of its head e⁶, substantially as indicated in Figs. 1 and 2. This loop may be made in many ways, as will be obvious; but in order to secure the greatest possible lightness, strength, cheapness, and durability and at the same time prevent its cutting or otherwise injuring the material of any waist which it may be used to fasten I preferably construct it as follows: I first take a piece of round wire and bend it so as to form the upper end f⁴ of the opening F' and two laterally and oppositely extending arms f⁵ and bring its ends f⁶ around so as to be opposite each other, substantially as illustrated in Fig. 6. I then fasten the ends f⁶ together and strengthen and stiffen the device by means of a metal Y-shaped blank F², having two upwardly-extending arms f⁷ and a central downwardly-extending portion f⁸. I do this by bending the upper ends of the arms f⁷ down around the tops f⁹ of the arms f⁵ and the downwardly-extending portion f⁸ up around the ends f⁶ of the base portion f² of the loop, all substantially as shown in Fig. 7. This completes the loop. The enlarged portion f³ of the opening F' is left between the arms f⁷ of said blank. If desired, my device may be fastened on the inside of a waist; but where it is used

not only as a skirt-supporter, but as a means for holding a shirt-waist down, the button E is first suspended from the corsets. If an underwaist B is worn, it and the waist C are next put on, and finally the loop F is passed over the head of the button without removing the fabric between it and the button and then pulled down into the position in which it is shown in Figs. 1 and 2. This fastens all the parts together, and they are not liable to become accidentally disengaged.

In describing the preferred form of my device I have spoken of the means engaged by the skirt-loop as a "button;" but I wish to be understood as desiring to cover as equivalents other suitable means for suspending a skirt from the arms E² and as not confining myself to the use of a button.

I claim—

1. In a skirt-supporter, the combination with a guard-plate, of two arms independently pivoted to the upper part of said guard-plate so as to allow it to swing laterally, but prevent it swinging outwardly, an opening or openings in the lower part of said guard-plate and adapted to receive a cord for securing the lower part of said plate to the corset, and means for detachably securing the skirt to said guard-plate.
2. In a skirt-supporter loop, the combination of a wire bent to form an upwardly-extending portion with the opening f⁴, and the laterally-extending arms f⁵; and the Y-shaped piece F² bent around the tops f⁹ and the bases f², of said arms; substantially as shown and described.

HARRY A. HEINEMAN.
